UNITED STATES PATENT OFFICE.

BENJAMIN M. HARROD AND FREDERICK N. OGDEN, OF NEW ORLEANS, LA.

IMPROVEMENT IN CLOTH-MEASURING APPARATUS.

Specification forming part of Letters Patent No. 175,086, dated March 21, 1876; application filed January 29, 1876.

To all whom it may concern:

Be it known that we, BENJAMIN M. HARROD and FREDERICK N. OGDEN, both of the city of New Orleans, in the parish of Orleans and State of Louisiana, have invented a new and useful improvement in machines for tallying and making into rolls bagging and other fabrics, which improvement is fully set forth in the following specification, reference being had to the accompanying drawings, in which—

Figure 1 is a side elevation; Fig. 2, a back view of our machine. Fig. 3 is a cross-section of the tallying-cylinder, and Figs. 4, 5, 6, 7, and 8 are detailed views of parts of our invention.

The nature of our invention consists in certain constructions and combinations of parts, hereinafter described and specifically claimed, whereby the following objects are attained:

First, the fabric to be measured and put up into given sized rolls or bolts can be taken in large rolls directly from the loom or other place, and placed in our machine with the greatest convenience and facility.

Second, the quantity of material placed in each smaller roll can be measured while the fabric is being rolled from the large roll into the smaller rolls, and the quantities in each roll can be regulated at the will of the operator; and when the determined quantity is rolled upon the roller-shaft, the fact will be indicated to the operator by a sound.

Third, the edges of the fabric are caused to pass to the roll in lines at right angles to the axis of the roller-shaft, and thus the ends of the smaller rolls are kept perpendicular with the axis of said roller from center to circumference.

Fourth, the small rolls can be taken from the roller-shaft with facility, and said shaft used repeatedly for the same purpose, and while this is the case the shaft is strong and not liable to become deranged or inoperative.

In the drawings, A represents an open frame of simple construction, the basis of which is extended toward the front to serve as a support for the feed-rollers B, upon which the fabric C' is received as it comes from the loom. D D are friction-rollers, and E is a measuring-cylinder, the circumference of

which is equal to a yard, or any other unit of measurement, and the surface of which is provided with pricks or pins e, whereby the sliding of the fabric over the said cylinder is prevented, and both the fabric and cylinder are compelled to move at exactly the same rate of speed. The shaft of the cylinder E is provided with a single cog, e', which revolves with the said cylinder, and at each revolution thereof engages a tooth, f, of a counting-wheel, F, and pushes it forward. The said wheel F is pivoted to the frame A, at a, and is prevented from casual movement by the spring-pawl G, which is fastened to the frame A, and by its wedge-shaped head g takes in between the teeth f of the said counting-wheel. The wheel F is also provided with a cam, H, terminating with a step, h. Upon the said cam H a spring, I, fastened to the frame A, is made to bear, so that when it arrives at the step h of the cam H it suddenly slips off and comes down upon the face of the wheel F with a snapping sound, thereby indicating the finishing of the intended measurement. The fabric is passed from the roll C to the rolls D D D, and roller or cylinder E, and therefrom between guides K to a shaft, J.

The said guides K are plates or boards supported by horizontal sliding screw-bolts L, which are passed through the frame A, and screwed into the guides K, and which are provided with heads l outside of the frame.

A number of tension-springs, k, are fastened between the frame A and the guides K, whereby the heads l are kept close against the frame and the guides are kept at the proper distance from each other. The bolts L, may be screwed a greater or less distance into the guides and thereby made to adjust them to the width of the fabric. The springs k, are of such a tension as to yield to any slight variation in the width of the fabric, but not to a deflection from a right course.

The shaft J is composed of two equal halves, which are inversely the counterparts of one another, and both halves have a head, M, with a socket, m². The halves are formed with matching-surfaces j j and j' j'; those portions j j of said surfaces being parallel, and those j' j' being of a wedge form. The

wedge surfaces are formed outside of the parallel surfaces j , j' of the respective halves, that of one of the halves of the shaft being inversely the counterpart of the other half thereof, and the highest parts of these wedge-shaped edges fit against the lowest parts of the said edges, and thus when the two halves are placed upon one another and their free ends inserted into the sockets m^2 , a solid and longitudinally-braced shaft, which is tongued and grooved together and presents no gaps or projections, is produced.

In the cross-sectional views, Figs. 7 and 8 of the roller shaft J, the manner in which the halves fit in one another is clearly shown, and in Fig. 4 the wedged edges on the respective halves are plainly indicated. This shaft J has journals m , m' and cranks m' connected rigidly to the heads M, M, and by constructing it in the peculiar manner specified it is made to possess great strength, as the lighter ends of the respective halves are strengthened by the heavier ends thereof, and facilities for withdrawing the said halves from the roll of fabric are afforded as the friction against the wedged edges diminishes very rapidly in the direction in which the halves are pulled apart, and this friction is very slight at all times on account of the narrowness of these edges. When the halves of the shaft are united, the journals m thereof exactly fit the open journal-bearings N of the brackets n on the frame A, and thus the said shaft can be easily placed in and removed from its position as circumstances require.

Operation: If a piece of cloth or other fabric is to be measured off it is placed on the feed rollers B. The number of yards or other units of measure represented by the circumference of the cylinder E is counted off on the cogs f of the wheel F, beginning at a point back of the step h of the cam H. The cog e on the cylinder E is then moved back until it touches one of the cogs f of the wheel F, and the fabric is passed over the cylinder E up to the shaft J. The fabric is then wrapped around the sharp corners of the shaft J, which is then turned by means of the cranks m' , the guides K in the mean-

time keeping the fabric straight, and thereby insuring its being wound up straight and evenly on the shaft. As one tooth f after another is moved ahead by the cog e on the revolving cylinder E, the cam H slides under the free end of the spring I, and gradually lifts it until the spring arrives at the step h, and falls from said step and announces by sound the finishing of the measurement. The fabric is now cut off on the cylinder E, at the point where it is desired a new measurement shall begin.

Having thus described our invention, what we claim as our own, and desire to secure by Letters Patent, is—

1. A tallying and rolling machine, combining feed-rollers B, tension-rollers D, measuring-rollers E, having a cog, e, a counting-wheel, F, having a cam, H, spring I, and pawl G, adjustable guides K, and shaft J, all constructed and operating substantially as hereinbefore set forth.
2. The combination of the measuring-cylinder E, having pins e, the counting-wheel F, having a cam, H, with the step h, the spring I, and the pawl G, operating substantially as and for the purpose set forth.
3. The lateral guides K, the tension-springs k, and the adjustable sliding bolts L, having heads l, all constructed and operating substantially as and for the purpose set forth.
4. The shaft J, upon which the fabric is rolled, consisting of the halves j, having the wedge-shaped edges j' , which are outside of parallel matching or tongued and grooved portions of the shaft, and the journaled heads M, having the sockets m^2 , all constructed and operating substantially as and for the purpose set forth.

Witness our hands in the matter of our application for patent for improvement in machines for measuring and rolling cloth, fabrics, &c.

BENJAMIN M. HARROD.
FRED. N. OGDEN.
